MICHAEL SHANNON, OF MUNCIE, INDIANA.

WIRE-DRAWING SAFETY DEVICE.

1,171,984.

Specification of Letters Patent. Patented Feb. 15, 1916.

Application filed August 16, 1915. Serial No. 45,739.

To all whom it may concern:

Be it known that I, MICHAEL SHANNON, a citizen of the United States, and a resident of Muncie, county of Delaware, and State 5 of Indiana, have invented a certain new and useful Wire-Drawing Safety Device; and I do hereby declare that the following is a full, clear, and exact description thereof, reference being had to the accompanying 13 drawings, in which like letters refer to like parts.

The object of this invention is automatically to stop a wire drawing mechanism when the wire becomes entangled so as to prevent the breakage of the wire and also to 15 prevent accidents to workmen who might become entangled in the wire and might, unless the device were stopped, lose fingers, arms, or legs. This object is accomplished 22 by a particular arrangement whereby when the wire becomes entangled, the reel from which it is being unwound, will be bodily moved, and upon such movement will actuate particular means for causing the instant 25 stoppage of the actuating mechanism.

The chief feature of the invention consists in mounting the reel on a spindle or support which is mounted in a platform or base frame. To that end upon the frame a guideway 30 is provided extending toward the wire drawing part of the mechanism, and the base of the spindle or reel support rests flatly upon such base frame within the guideway and loosely, whereby it will be 35 held in place, under normal action, by the weight of the reel and wire, and yet will yield or slide toward the wire drawing part of the machine when the wire becomes caught or entangled. Also the spindle or 40 support for the reel, by merely resting loosely upon the base frame, enables the reel to be readily tilted over when a coil of wire is being placed upon it, thus making that laborious operation easier.

45 The full nature of the invention will be understood from the accompanying drawings and the following description and claims:

In the drawings Figure 1 is a side elevation of the wire drawing mechanism with parts in normal operating position. Fig. 2 is the same with parts in position for stopping the mechanism on account of an entanglement of the wire. Fig. 3 is a section 55 on the line 3—3 of Fig. 1. Fig. 4 is a sec-

tion on the line 4—4 of Fig. 1. Fig. 5 is a section on the line 5—5 of Fig. 2.

There is a fixed base or frame formed of the parts 11 and 12 rigidly secured in place, and upon the part 11 of the base there is secured a wire drawing frame 13 having on the upper right hand end a wire drawing plate 14 through which a wire 15 is drawn from a reel 16. After the wire passes through said wire drawing plate, it is wound on a reel 17 loosely mounted on the vertical shaft 18 in said wire drawing frame 13. This shaft is driven by a bevel gear 19 meshing with a gear 20 on the driving shaft 21. The reel 17 has an angular recess 22 on its under side adapted to fit over and interlock with a clutch block 23 which is secured on the shaft 18 so that when the reel 17 is in its down position, as in Figs. 1 and 4, it will be driven by the clutch block 23, 75 but when elevated as in Figs. 2 and 5, the reel 17 will not be driven. The reel 17 is disengaged or unlocked from its driving means by a lever 25 fulcrumed between its ends at 26 to the frame 13 and with one end 80 turned and projecting under the reel 17 so as to elevate it when the lever is actuated. Said lever is actuated by a link 27 pivoted to its other end and said link is pivoted to the lever 28 fulcrumed at its end at 29 85 to the frame 13, and at its other end it is actuated by a link 30 with which a cable 31 is connected at its lower end and said cable passes over a sheave wheel 32 mounted in the bracket 33 secured to the base. 90

The cable 31 is connected to a lever 34 by a connecting rod 35, or in any other suitable manner, so as to be longitudinally adjustable. The lever 34 is fulcrumed between its ends at 37 to a bracket 38 extending upward from the base. The upper end of the lever 34 is pivotally connected with a rod 39 and runs to the upper end of the spindle 40 on which the reel 16 is loosely mounted. Said spindle 40 has a base 41, as seen in Fig. 3, which is slidable in a guideway formed by angle guide bars 42 parallel with each other and extending toward the wire drawing frame. The connecting rod 39 has its right hand end looped so as to fit loosely 105 over the reduced upper end of the spindle and therefore may be readily elevated out of the way, as shown in Fig. 1, when it is desired to remove the reel or put on a new reel. 110

While the device is operating, the parts are in the positions shown in Fig. 1. When, however, the wire becomes entangled so as not to be readily unwound from the reel 16, it will draw the reel 16 toward the wire drawing device, as shown in Fig. 2. That movement will cause the connecting rod 39 to actuate the lever 34 and, through the intermediate train of the mechanism, the reel 17 will be lifted out of engagement with its actuating mechanism and the machine stopped, until the wire can be untangled and the parts replaced in their normal positions. The weight of the reel 16 and wire on it creates sufficient friction between its base 41 and the platform or base of the machine 12 to hold the reel normally in proper position and to supply sufficient resistance to the pull of the wire 15 as it is being drawn, likewise a sufficient resistance between the reel 16 and the spindle 40 for holding the wire 15 taut. The connection of the rod 39 with the spindle 40 is such that any ordinary wire reel can be used, and the reel can be tipped over or manipulated in any manner that the workmen may desire. On account of the great weight, from one hundred fifty to three hundred pounds of the coil, it is very desirable to tip the reel in order to reduce the lift in placing the coil on the reel. This can be done in this device by lifting the rod 39 and tipping the reel and spindle over to make it easy to put on the heavy rod or wire.

The ease of operating and manipulating the device is important, because unless a safety device in such mechanism requires little labor or attention on the part of the workmen, they will neglect it after a time and not go to the trouble of placing it in position and thus leave the device so that it will endanger the workmen when the wire becomes entangled, and be liable to break the wire. This difficulty is obviated by the arrangement above described which is so simple and easily operated that it helps rather than hinders the labor of the workmen.

The invention claimed is:

1. A wire drawing apparatus including wire drawing means, a reel from which the wire is drawn by said wire drawing means, a spindle on which the reel is loosely mounted which has a base, a base frame on which the base of the reel spindle loosely rests so as to be slidable toward the wire drawing means when the wire becomes en-

tangled, and means actuated by such movement of the reel for stopping the operation of the wire drawing means.

2. A wire drawing apparatus including wire drawing means, a reel from which the wire is drawn by such wire drawing means, means for slidably mounting said reel so that when said wire is entangled it will draw the wire bodily toward the wire drawing means, a lever, means actuated thereby for stopping the wire drawing means, and a connecting rod pivoted at one end of said lever and the other end adapted to loosely engage the end of the spindle so as to be readily removable therefrom and whereby when the reel slides toward the wire drawing means it will actuate said lever through the agency of said rod.

3. A wire drawing apparatus, including wire drawing means, a reel from which the wire is drawn by said wire drawing means, a spindle on which the reel is mounted which has a base, a base frame on which the base of the reel spindle rests loosely so as to be slidable toward the wire drawing means when the wire becomes entangled, a lever, means actuated thereby for stopping the wire drawing means, and a connecting rod pivoted at one end of said lever and the other end adapted to loosely engage the upper end of the reel spindle so as to be readily removed therefrom, and whereby, when the reel slides toward the wire drawing means, it will actuate said lever through the agency of said rod.

4. A wire drawing apparatus, including wire drawing means, a reel from which the wire is drawn by said wire drawing means, a spindle on which the reel is mounted, which has a base and has its upper end reduced, a base frame on which the base of the reel spindle rests loosely so as to be slidable toward the wire drawing means when the wire becomes entangled, a lever, means actuated thereby for stopping the wire drawing means, and a connecting rod pivoted at one end of said lever and the other end provided with a loop for loosely engaging the reduced upper end of the spindle. 105

In witness whereof, I have hereunto affixed my signature in the presence of the witnesses herein named.

MICHAEL SHANNON.
